United States Patent Office

Des. 205,190
Patented July 5, 1966

205,190

BARREL LIFTER

Roy S. Trimble, 1021 Capitol, Beacon Hill Station,
San Antonio, Tex.

Filed Oct. 14, 1965, Ser. No. 87,489

Term of patent 14 years

(Cl. D41—1)

FIG. 1

FIG. 2

FIG. 3

FIG. 4

FIGURE 1 is a top plan view of my new design for a barrel lifter;

FIGURE 2 is a side elevational view thereof;

FIGURE 3 is a bottom plan view thereof; and

FIGURE 4 is an end view as seen from the left of FIGURE 1.

I claim:

The ornamental design for a barrel lifter, as shown.
